AUTOMOBILE

Richard A. Teague, Rochester, Mich., assignor to Studebaker-Packard Corporation, a corporation of Michigan

Application March 17, 1954, Serial No. 29,574

Term of patent 14 years

(Cl. D14—3)

The characteristic features of my design reside in the portions shown by means of solid lines in the drawings.

I claim:

The ornamental design for an automobile, as shown and described.
